UNITED STATES PATENT OFFICE.

JAMES H. WAGENHORST, OF JACKSON, MICHIGAN.

LATCH PLATE FOR TRANSLIT RIMS.

Application filed January 23, 1922. Serial No. 531,089.

To all whom it may concern:

Be it known that I, JAMES H. WAGENHORST, a citizen of the United States, residing at Jackson, in the county of Jackson and State of Michigan, have invented a certain new and useful Improvement in Latch Plates for Transplit Rims, of which the following is a full, clear, and exact description, reference being had to the accompanying 10 drawings.

This invention relates generally to demountable tire carrying rims for automobiles and more particularly to a novel construction of latch for connecting together 15 the ends of a transplit rim, the object being to provide a cheap, simple and efficient form of latch, which when closed will hold the rim ends against both lateral and radial separation, and another object is to provide 20 a device of such a nature that the movable part can be easily manipulated either to lock or unlock the parts, and which when once in place will remain firm.

With these objects in view the invention 25 consists broadly in connecting a bridge plate rigidly to one end of the rim, upon the inner face, so that it will project beyond the split, providing said projecting portion with an opening which receives an inwardly 30 projecting stud attached to the opposite end of the rim and attaching a latch pivotally to the end of the bridge plate and which is adapted to be brought into engagement with the stud, which may be notched or grooved 35 to receive the end of said latch, or the stud may be headed and the latch notched or recessed to fit the shank of the stud, and in each construction hold the parts against disengagement.

40 The invention consists also in certain details of construction hereinafter fully described and pointed out in the claims.

In the drawings forming a part of this specification, Fig. 1 is a longitudinal sectional view of one form of rim latch embodying my invention; Fig. 2 is a plan view of the same; Fig. 3 is a sectional view of a slightly different form and Fig. 4 a plan view of the same; and Fig. 5 is a plan view 50 of a slight modification.

Referring to the drawings A designates one end of a tire carrying rim and B the other end thereof, the division point or split being indicated at C.

A bridge plate D is rigidly connected to 55 the end A upon the inner side thereof and projects beyond the split C said plate being preferably secured by a rivet E. The projecting portion has an opening F produced 60 therefrom to receive an inwardly projecting stud G attached to the end B of rim, the shank of said stud being riveted in the base of the rim as shown.

A latch H is pivoted to the bridge plate D, preferably at its free end, and turns upon 65 its pivot I and its free end is intended to be moved into a notch, recess or groove K, cut in the side of the stud G next to the pivot I and when this latch is thus brought into locked relation with the stud it is obvious 70 that the bridge plate cannot become disengaged and that the rim ends will therefore be held against both radial and lateral movement.

The latch plate is flanged or upset at one 75 side as shown at L and this upset edge or flange serves as a stop to limit the engaging movement and it also aids in disengaging the latch as it provides a striking or tapping point for a tool when it becomes necessary 80 to force the latch end out of engagement with the stud.

In Fig. 3 the latch plate D' is offset at D² and the stud G' has a head G² which is somewhat larger than the shank, and the latch H' 85 is pivoted at I' and is provided with a notch or recess H² which receives the shank of the stud when the latch is moved over the head G² which fits into the opening F' near the free end of the bridge plate. The latch has 90 the same upset edge or flange L serving the same purpose.

The offset D² in the bridge plate also permits the introduction of a screw driver or tire tool for separating the rim ends after 95 the latch has been disengaged.

In Fig. 5 the bridge plate D³ is flat instead of offset and the latch H³ is upon the inner face thereof as in Figs. 1 and 2 but the stud G³ is headed and the latch is notched or recessed to fit the shank between the head of stud and bridge plate. The same upset edge or flange L is also provided.

It will thus be seen that I provide a cheap, simple and efficient construction of latch 105 plate for locking the ends of a transplit rim and also one which can be readily applied and likewise easily manipulated.

Having thus described my invention, what I claim is:

1. The combination with a transplit rim, of a bridge plate attached to one end of the rim and having an opening beneath the other end, a stud carried by said other end and engaging said opening, and a latch pivoted to said bridge plate and engaging said stud, said bridge plate being offset.
- 10 2. The combination with a transplit rim, of a bridge plate connected to one end, and projecting beneath the other end, and having an opening in said projecting portion, a stud carried by the other end of the rim, and engaging the opening in the bridge plate, a latch pivoted to the bridge plate and engaging said stud, said latch having a flange at one side thereof.
- 15 3. The combination, with a transplit rim, of a stud carried by one end of the rim, a bridge plate carried by the other end of the rim and having an opening to receive the stud and a latch pivoted to the bridge plate

for engagement with the stud, one of said members being recessed, the bridge plate being offset. 25

4. The combination, with a transplit rim, of a stud carried by one end of the rim, a bridge plate carried by the other end of the rim and having an opening to receive the stop and a latch pivoted to the bridge plate 30 for engagement with the stud, one of said members being recessed, the bridge plate being offset and the latch having a flange at one side. 35

5. The combination with a transplit rim, of a headed stud carried by one end of the rim, a bridge plate carried by the other end of said rim and having an opening to receive the head of the stud, and a recessed latch plate pivoted to the bridge plate, and provided with a flange at one side. 40

In testimony whereof, I hereunto affix my signature.

JAMES H. WAGENHORST.
